UNITED STATES PATENT OFFICE

BERNARD ROGGE, OF BALTIMORE, MARYLAND, ASSIGNOR TO HARRINGTON & KING PERFORATING COMPANY, OF CHICAGO, ILLINOIS, A CORPORATION OF ILLINOIS

DESIGN FOR A GRILLE PANEL

Application filed December 5, 1931. Serial No. 41,971. Term of patent 14 years.

To all whom it may concern:

Be it known that I, BERNARD ROGGE, a citizen of Germany, residing at Baltimore, in the county of Baltimore and State of Maryland, have invented a new, original, and ornamental Design for Grille Panel, of which the following is a specification, reference being had to the accompanying drawing, forming a part thereof.

In the drawing:

The figure is a face view of a portion of a grille panel embodying my new design.

It may be understood that the thickness of such a grille may vary, depending upon the

material of which it is constructed and the use for which it is intended, but that in all cases the thickness will be small relatively to the area. The portion of the grille illustrated represents somewhat more than a complete repeat unit. The grille, being relatively thin and flat, is adapted to be used as a panel for a door, screen, radiator or similar article.

I claim:

The ornamental design for a grille panel substantially as shown and described.

BERNARD ROGGE.
